UNITED STATES PATENT OFFICE

115,535

DESIGN FOR A CABINET OR SIMILAR ARTICLE FOR SMOKING TOBACCO AND GAME EQUIPMENT

Edward M. Williams, Detroit, Mich.

Application October 26, 1938, Serial No. 80,674

Term of patent 7 years

To all whom it may concern:

Be it known that I, Edward M. Williams, a citizen of the United States, residing at Detroit, county of Wayne, State of Michigan, have invented a new, original, and ornamental Design for a Cabinet or Similar Article for Smoking Tobacco and Game Equipment, of which the following is a specification, reference being had to the accompanying drawing, forming part thereof.

In the drawing:

similar article embodying my new design, and Figure 2 is a top plan view thereof, on an enlarged scale.

The side and end of the cabinet not shown in the drawing are substantially similar to the side and end illustrated in the drawing.

I claim:

The ornamental design for a cabinet or similar article for smoking tobacco and game equipment, as shown and described.

EDWARD M. WILLIAMS.
